V. C. SPARKS.
COMBINED VAPORIZER AND HOMOGENIZER FOR EXPLOSIVE ENGINES.
APPLICATION FILED MAR. 16, 1916.

UNITED STATES PATENT OFFICE.

VERNON C. SPARKS, OF SAN FRANCISCO, CALIFORNIA.

COMBINED VAPORIZER AND HOMOGENIZER FOR EXPLOSIVE-ENGINES.

1,211,775.

Specification of Letters Patent.

Patented Jan. 9, 1917.

Application filed March 16, 1916. Serial No. 84,703.

To all whom it may concern:

Be it known that I, VERNON C. SPARKS, a citizen of the United States, residing at San Francisco, in the county of San Francisco, State of California, have invented a new and useful Combined Vaporizer and Homogenizer for Explosive-Engines, of which the following is a specification in such full and clear terms as will enable those skilled in the art to construct and use the same.

This invention relates to a combined vaporizer and homogenizer for explosive engines and its object is to provide means whereby heavy fuel such as distillates or coal oil may be used as a substitute for gasoline.

An object of the invention is to provide a vaporizer which will be capable of starting the engine on a comparatively heavy fuel even when the fuel is cold, means being provided in the vaporizer for breaking up the fuel in exceedingly fine particles, thereby producing a sufficient quantity of explosive gas to give the engine enough power to start and as soon as the engine has turned over a few times the heat from the exploded gas will be sufficient to cause the generator to deliver enough gas to run the engine with its full power.

An embodiment of the invention is shown in the drawing in which the same reference numeral is applied to the same portion throughout, but I am aware that there may be many modifications thereof.

Figure 1 is a side elevation of an explosion engine having this invention applied thereto, and Fig. 2 is a vertical sectional view through the generator showing the position of the screens which break up the incoming fuel into a gas sufficiently finely disseminated to explode.

In the drawing the numeral 1 indicates a common type of four cylinder engine having the exhaust manifold 2 and inlet manifold 3 for all of the cylinders. This device is installed on the inlet manifold 3 as indicated at 4 and it has a pipe 5 extending from the exhaust manifold therein and another pipe 6 extending to the exhaust discharge pipe 7 to prevent the discharges of gas from making any more noise than they would ordinarily when discharged through the muffler.

This heater has a flanged coupling 8 secured to its lower end to which the carbureter 9 is secured, said carbureter being of any well known type, and having its

throttle valve operated by means of a rod 10 in a well known manner. The heater consists of a cylinder 4 having an inlet fitting 12 at its upper end and a fitting 13 at its lower end, which fittings are connected with the pipes 5 and 6 respectively. Within the heater there is a thin metal tube 14 which has a flange at 15 to hold it in position and said tube extends entirely through the heater 4. This tube has a fine wire screen extending transversely across the top thereof as indicated at 16, said screen being large enough to be seated on top of the heater to hold the remaining screens and the rod to which they are connected in the proper place.

The screen 16 is held in place between the manifold 3 and heater 4 by means of the bolts 17 and 18 and at its center it has a threaded rod 19 extending therethrough and connected therewith by means of suitable nuts, which rod supports five other fine screens at suitable distances from each other. The screens 20, 21, 22, 23 and 24 are all cut out of a disk somewhat larger than the pipe or tube 14 within which they are placed; so that the edge of each disk points downward and is in contact with the tube 14 a considerable distance, thereby assisting in absorbing the heat and transmitting it to the fuel passing through the tube. The tube 14 is made of such size with respect to the opening of the carbureter that the screens therein will allow substantially the same free area as the free area of the carbureter, thereby preventing its operation from being interfered with in any way.

With this heater installed on an explosion engine it is possible to run the engine with a grade of fuel much heavier than is possible with the ordinary carbureter not having a heater installed between the carbureter and manifold, and it is also possible to start the engine on a heavy grade of fuel even when the heater is cold for the reason that the screens stop all large particles of the fuel and allow only the most finely divided particles thereof to pass whereby a sufficiently explosive mixture is obtained to start the engine, and as soon as the engine has been run for a short time the engine will run up to its full power and speed because the screens absorb enough heat to properly vaporize the fuel.

An advantage of this heater lies in the fact that not only is it possible to use a

heavier grade of fuel than is possible with the ordinary carburetor, but that by heating the fuel in this way before passing it into the engine much of the trouble of an engine 5 due to carbon is avoided, since combustion is greatly improved.

Having thus described my invention what I claim as new and desire to secure by Letters Patent of the United States, is as follows; express reservation being made of permissible modifications:

1. A gas generator for explosion engines comprising a tubular extension of the inlet manifold, a heating chamber formed around 15 said tubular extension of the inlet manifold, a pipe leading from the exhaust manifold to the heating chamber, a carburetor connected with the heater, a plurality of inverted cup shaped screens frictionally connected with the interior of the heater through 20 which the fuel must pass to reach the engine

and means to hold the screens in a fixed position.

2. A gas generator for explosion engines comprising a tubular extension of the inlet 25 manifold of the engine, a heating chamber formed around said tubular extension of the inlet manifold, a pipe leading from the exhaust manifold to said heating chamber, a carburetor connected with the lower end of 30 the heater, a transversely placed screen across the upper end of the heater, a rod passing through the center of said screen, and a plurality of other screens connected to said rod and frictionally engaging said 35 tubular member whereby the wire screens are heated to gasify the fuel as it passes through the heater.

In testimony whereof I have hereunto set my hand this 10th day of March, A. D. 1916. 40

VERNON C. SPARKS.
